UNITED STATES PATENT OFFICE

ALBERT C. BENNETT, OF TOPEKA, KANSAS

COMBINED DINING SET AND CABINET

Application filed April 30, 1928. Serial No. 273,975.

My invention relates to a combined dining set and cabinet.

The object of my invention is to provide a cabinet as a container for the table and the seats, the cabinet also having drawers and doors accessible to storage with shelves in the cabinet.

A further object of my invention is to provide an arrangement functioning as a dining set portably arranged and inexpensive consideraing the service acquired thereby.

These and other objects will hereinafter be more fully explained, reference being had to the accompanying drawings forming a part of this specification, wherein like characters will apply to like parts throughout the different views.

Referring to the drawings:

Fig. 1 is a perspective view of the cabinet containing the table, seats, and drawers, parts removed for convenience of illustration.

Fig. 2 is a plan view, parts removed for convenience of illustration.

Fig. 3 is an end view of the cabinet showing a table and seat unfolded to operative position.

Figs. 4, 5, and 6 show the methods of unfolding the seat from its container.

Fig. 7 is a plan view of Fig. 5.

Fig. 8 is a sectional view taken on line 8—8 in Fig. 6, showing the leg in elevation.

Fig. 9 is an enlarged sectional detailed view of the seat and legs folded, and the hinge means therefor.

The invention herein disclosed consists of a cabinet having corner posts 1 functioning as legs, and a centrally positioned leg 2 at the front. The last said leg functions as a support for the table top when extended, as hereinafter described. In each of the opposite ends of the cabinet is a container 3, said containers hingedly connected to their respective bottom rails 4, and having a pull 5, as means to rock the container element outward as shown by dotted lines A in Fig. 1; and when rocked outward to horizontal position as shown at B in Fig. 2, the seat and leg members contained therein will be unfolded, the process of which is shown in

Figs. 4, 5, and 6, later described. The forward end of the container is provided with an end member 6 to which the first seat member is hingedly connected as shown at C in Figs. 2 and 3. The opposite end of the container is supported by a diagonally positioned brace member 7, one end of the member pivotally connected to the rear end of the container while the other end is pivotally connected to the cabinet, the brace having a joint in the center as at D, as collapsible means therefor.

Positioned above each of the seat containing elements is a drawer 9 slidably engaging, one of the drawers being partly pulled outward as shown at E in Fig. 2. The front of the cabinet is inclosed by a pair of doors 10, the said doors hingedly connected to their respective corner posts, the opposite sides of the doors being separated to receive the leg 2 slidably engaging therebetween. Positioned within the cabinet rearward the said doors and extending across and in close proximity to the seats is a shelf 11, having a supporting member 12 for each end thereof as shown in Fig. 1.

It is now clearly shown that table linens may be placed on the shelf 11 or the bottom of the cabinet as shown at 13, and the drawers may be for the reception of silverware, napkins, or other articles.

The cabinet is also shown to have a permanently arranged top 14, underneath which are positioned table-top members 15 and 16 and extension members 17, 18, and 19, the said members being tongued and grooved together as shown by dotted lines F. The member 17 slidably engages under the top member 16, the said top member being rigidly attached to the frame 18. The said top member 16 has a stop as shown at 20 in Fig. 2, and being so stopped in its outward movement, the frame 17 is free to extend outward as shown in Fig. 2. The said frame is a support for the top member 15, which is hingedly attached to member 16 as a rigid support therefor. It will be understood that the top member 15, being hinged to top member 16, will fold back thereon prior to

retracting the table members within the cabinet.

The leg 2 is connected in the center of the outer rail 17' and is rigidly braced to an intermediate member of frame 17 as shown by dotted lines 17'', the bracing means being a bracket 21 as shown in Fig. 3.

To unfold each of the seats to their relative position to the table top as shown in Fig. 2, the containers 3 are rocked outward, and the legs 22 and their respective seat members 23 to which they are hingedly attached and braced by members 24, later described, are also rocked to their operative position. The rocking of said legs and seat members is shown by dotted lines in Figs. 3, 4, 5, and 6. Fig. 3 shows the correct open position; Fig. 4 shows the first movement; Fig. 5 shows the second movement; and Fig. 6 shows the third movement.

At the inner ends of legs 22, as shown in Figs. 3 to 9 inclusive is a furring strip 25 rigidly connected to the seat 23, and on which said leg is attached by a hinge 26, whereby the leg 22 will fold closely on the oppositely positioned leg 22, all of which is clearly shown in Fig. 9. As a means to hingedly connect the seat members to the frame 6, I have provided pairs of Z-shaped hinges 27, so that when rocked to position the said seats and legs will snugly fit in their respective frames. In each of the two outer legs of the seats, now being identified by the character G, is a groove 28 adapted to receive the brace members 24 when folded on the seat, as shown in Fig. 7; and the eye 29 will enter a socket 30 in the back of the leg on the opposite end of the seat member, as shown in Fig. 7, by which means the said seat and legs are free to fold in snug engagement, as shown by dotted lines in Fig. 3, or as illustrated in Figs. 4 and 9.

The cabinet and table equipment, herein disclosed, may be made of metal or suitable materials at the discretion of the manufacturer. The proportions may also be changed from those shown in the drawings, and such other modifications may be employed as lie within the scope of the appended claims.

Having fully described my invention, what I claim as new and desire to secure by Letters Patent is:

1. In a combined dining set and cabinet, a cabinet having a collapsible seat carrying frame positioned in each end of the cabinet, the said seat carrying frame hingedly connected to the cabinet and adapted to rock outward preparatory to unfolding the members of their respective seats, and a pair of doors to inclose the front, the doors being separated from each other when closed, a collapsible frame attached to the cabinet and slidably engaging therein, a leg on the outwardly extending frame, the leg being positioned between the doors when the frames are retracted normally within the cabinet, a top

having a plurality of members hingedly connected and carried by the collapsible frames, all substantially as shown.

2. In a combined dining set and cabinet, a cabinet and dining set of the kind described, a collapsibly arranged table top and collapsible carrying elements therefor contained and supported by the cabinet, and doors arranged beneath the top and collapsible carrying elements, and being separated from each other to snugly receive the carrying element for the table top elements, a frame hingedly connected on each end of the cabinet, each of the frames having a collapsible brace member to support the rear end thereof, and a front end member positioned at right angles and rigidly attached, a plurality of seat members, one of which is hingedly connected to the end member of the frame, the said seat members having hingedly connected legs and means to brace the same when unfolded, the said seat and leg members adapted to fold within the frame and rocked within the cabinet by the frame as disappearing means therefor, a plurality of frame members arranged to slidably engage with each other as collapsible means to eject from or retract within the cabinet, the inside or outward extending frame members having a leg as supporting means therefor, a table top carried by the frame, and being in two parts hingedly connected, so that the outer member will lap back on an inner member when the top is retracted within the cabinet.

3. In a combined dining set and cabinet, a cabinet and dining set as an article of manufacture, a cabinet having a stationary top, a collapsibly arranged table slidably engaging beneath the top and concealed thereby, and a collapsible frame having a leg member movable therewith, a pair of collapsibly arranged seats carried by a frame element respectively and positioned on each end and adapted to rock, causing the seats to disappear within the cabinet, a pair of doors to inclose the front of the cabinet, the doors being spaced apart to receive the leg member as bracing means therefor when the cabinet is being moved and also as an alignment means with the corners of the cabinet, all as and for the purpose described.

In testimony whereof I affix my signature.

ALBERT C. BENNETT.
